FIG. 3

INVENTOR
THOMAS ALBERT SCANLON

BY
William Frederick Werner
ATTORNEY

STETHOSCOPE

This invention relates to stethoscopes and more particularly to a new construction which is self-supporting in ear canals and is provided with adjustable means for varying the pressure on the ear canals.

An object of the present invention is to preform the end portions of a pair of plastic tubes into an open loop so as to render them resilient in a diametrically opposite plane and to provide means for varying the resilient pressure exerted in the diametrically opposite plane.

Another object of the present invention is to provide ear tips of a preselected material and configuration so that the ear tips will support the respective, loop ends of the plastic tubes in, respective, ear canals.

Still another object of the present invention is to provide a stethoscope of inexpensive construction and extremely light in weight and comfortable to the wearer when supported in the orifices of the ears.

Other objects of the present invention will become apparent in part and be pointed out in part in the following specification and claims.

Like reference numerals refer to like parts in the following drawings in which:

FIG. 1 is a side elevational view of the new and improved stethoscope;

FIG. 2 is a vertical medial view through FIG. 1;

FIG. 3 is an enlarged vertical cross-sectional view through an ear tip.

Referring to the drawings with more particularity, a sound tube head set or stethoscope, indicated generally by reference numeral 10, includes two flexible tubes 11, 12 of the type produced by the extrusion method for plastics and which may be fabricated from polyvinylchloride. Tubes 11 and 12 have separate acoustical or sound wave passageways 16, 17.

The two flexible tubes 11 and 12 may be fastened together as by heat sealing for part of their length, as shown at 13. One end of tubes 11 and 12 may be fastened in a jack 14 which can be plugged into a sound collector, transducer or sound receiver (not shown).

A sleeve 15 is frictionally mounted upon tubes 11 and 12 for sliding movement along said tubes in the length away from where the tubes 11, 12 are fastened together.

The respective ends 11A and 12A of tubes 11 and 12 are placed in a form and heat set into a reverse curve which forms a bowlike shape in each end; with the respective ends diametrically facing each other to form a resilient open loop.

Sleeve 15, slideable upon tube ends 11A and 12A, dictates the size of the loop and the tension exerted by the loop ends 11A and 12A toward each other, through the movement of sections 11B and 12B of the reverse curve toward and away from each other.

Reference is made to FIG. 3 wherein an ear tip, generally indicated by reference numeral 20, is illustrated.

Ear tips 20 are fabricated from natural or synthetic rubber and are preferable molded from sponge rubber so as to be soft and pliable and easily deformable into the shape of an ear canal.

It has been found through empirical effort that an ear tip having a length "L" of seventeen thirty-seconds of an inch, an entering end diameter "D" of three-sixteenths of an inch, a major body diameter "M" of three-eighths of an inch, and a flange 21, will comfortably stay inserted in most ear canals even though a head is moved in routine daily movement.

A tapered or curved surface 23 connects dimension "D"

with dimension "M" to form the desired contour for the ear tip.

Ear tip 20 is axially provided with a sound passageway 25 and an axial bore 26.

The outer ends of tubes 11A, 12A are inserted, respectively, in axial bores 26 so as to connect sound wave or acoustical passageways 16 and 17 in communication with sound passageways 25.

The ear tips 20 are fastened respectively, FIG. 2, to the outer ends of tubes 11A, 12A by means of the inherent resilience of the material, or by heat sealing, cement or a drive fit in axial bores 26. Flange 21 is a stop to limit the extent that the ear tip 20 may be inserted into an ear canal.

Having shown and described a preferred embodiment of the present invention, by way of example, it should be realized that structural changes could be made and other examples given without departing from either the spirit or scope of this invention.

I claim:

- 20 1. A stethoscope for conducting sound waves comprising a pair of flexible tubes, a sleeve frictionally mounted for sliding movement upon said tubes, each tube having a reverse curve section adjacent one end to provide tube ends diametrically opposite each other to form a resilient open loop, and two ear tips, fastened respectively, to the outer ends of said pair of tubes, said sleeve increasing or decreasing the resiliency of said open loop.
- 30 2. A structure as claimed in claim 1 being further characterized by: said pair of ear tips being fabricated from soft pliable material having a tapered outer surface wherein one end of the taper approximates three-sixteenths of an inch, the opposite end of the taper approximates three-eighths of an inch and the length of the taper approximates seventeen thirty-seconds of an inch.
- 35 3. In the manufacture of a stethoscope for conducting sound waves, the method comprising the steps of:
  - a. extruding a plastic tube of a required cross section;
  - b. cutting said tube into appropriate lengths;
  - c. laying two lengths of tube side by side to provide a pair of tubes;
  - d. fastening said tubes together a selected portion of the appropriate lengths;
  - e. sliding a sleeve over said pair of tubes at the unfastened portion of the appropriate lengths;
  - f. providing a reverse curve section adjacent one end of each of said pair of tubes to provide tube ends diametrically opposite to each other; and
  - 40 g. heat setting the reverse curve sections to form a resilient open loop.
- 45 4. In the manufacture of a stethoscope for conducting sound waves, the method comprising the steps of:
  - a. extruding two plastic tubes, each of required cross section;
  - b. bonding the two tubes together at the mouth of the extruder to form a web between the two tubes;
  - c. cutting said tubes into appropriate lengths;
  - d. severing the web to separate the two tubes a selected portion of the appropriate length;
  - e. sliding a sleeve over said pair of tubes at the severed portion of the appropriate lengths;
  - f. providing a reverse curve section adjacent one end of each of said pair of tubes to provide tube ends diametrically opposite to each other; and
  - 50 g. heat setting the reverse curve sections to form a resilient open loop.
- 55 5. In the manufacture of a stethoscope for conducting sound waves, the method comprising the steps of:
  - a. extruding two plastic tubes, each of required cross section;
  - b. bonding the two tubes together at the mouth of the extruder to form a web between the two tubes;
  - c. cutting said tubes into appropriate lengths;
  - d. severing the web to separate the two tubes a selected portion of the appropriate length;
  - e. sliding a sleeve over said pair of tubes at the severed portion of the appropriate lengths;
  - f. providing a reverse curve section adjacent one end of each of said pair of tubes to provide tube ends diametrically opposite to each other; and
  - 60 g. heat setting the reverse curve sections to form a resilient open loop.
- 65 6. In the manufacture of a stethoscope for conducting sound waves, the method comprising the steps of:
  - a. extruding two plastic tubes, each of required cross section;
  - b. bonding the two tubes together at the mouth of the extruder to form a web between the two tubes;
  - c. cutting said tubes into appropriate lengths;
  - d. severing the web to separate the two tubes a selected portion of the appropriate length;
  - e. sliding a sleeve over said pair of tubes at the severed portion of the appropriate lengths;
  - f. providing a reverse curve section adjacent one end of each of said pair of tubes to provide tube ends diametrically opposite to each other; and
  - 70 g. heat setting the reverse curve sections to form a resilient open loop.
